UNITED STATES PATENT OFFICE.

THOMAS A. KILLMAN, OF NASHVILLE, TENNESSEE.

STEAM-PUMP.

1,367,980.

Specification of Letters Patent.

Patented Feb. 8, 1921.

Application filed June 3, 1919. Serial No. 301,502.

To all whom it may concern:

Be it known that I, THOMAS A. KILLMAN, a citizen of the United States, residing at Nashville, in the county of Davidson and 5 State of Tennessee, have invented certain new and useful Improvements in Steam-Pumps, of which the following is a specification.

This invention relates to pumping apparatus and more particularly to an improvement in steam pumps of that type in which the water is elevated and discharged respectively by the creation of a partial vacuum by the condensation of steam, and the exertion 15 of pressure by live steam.

One of the primary objects of the present invention is to provide a pumping apparatus of the class mentioned so constructed that there will be little loss of steam through 20 condensation such as might take place if a relatively large surface area of cold water were exposed to the live steam, so that by the apparatus the maximum efficiency of the live steam is obtained with a consequent 25 economy in fuel consumption.

Another object of the invention is to provide pumping apparatus so constructed that in operation the water pumped thereby will not have its temperature appreciably raised 30 through absorption of heat from the live steam through the pressure of which it is discharged from the apparatus. In other words, the invention has as its object, in this respect, to provide for the delivery of cold 35 water from the apparatus, any portion of the volume of water circulating through the apparatus and having its temperature appreciably raised through contact with the live steam being returned to the steam generating 40 portion of the apparatus and its heat units being thus conserved.

A further object of the invention is to provide in an apparatus of this class a condensing means for the steam of maximum 45 efficiency so as to provide for rapid and complete condensation of the exhaust steam in creating the partial vacuum for elevating or drawing water into the apparatus to be discharged therefrom.

Another object of the invention is to provide an apparatus which will be wholly automatic in its operation and in which the valve for controlling the supply of live steam to the cylinders of the apparatus will 55 be actuated through the medium of the steam exhausted from the said cylinders.

A further object of the invention is to provide a novel arrangement of check valves for controlling the exhaust of steam from the cylinders of the apparatus and a novel 60 float device for controlling the opening and the closing of these valves.

In the accompanying drawings:

Figure 1 is a view in elevation of the apparatus embodying the present invention; 65

Fig. 2 is a vertical sectional view therethrough, parts being shown in elevation;

Fig. 3 is a horizontal sectional view taken substantially on the line 3—3 of Fig. 2;

Fig. 4 is a vertical front to rear sectional 70 view taken substantially on the line 4—4 of Fig. 1;

Fig. 5 is a detail vertical sectional view 75 through the three-way throttle valve of the pump.

The pumping apparatus embodying the present invention includes a boiler indicated in general by the numeral 1 and preferably of the upright fire tube type although any other type of boiler or steam generator 80 might be employed if desired, in view of which fact a more specific description of the boiler or generator is deemed unnecessary.

The pumping apparatus further includes two pumping cylinders one indicated in general by the numeral 2 and the other in general by the numeral 3, these pumping cylinders being preferably arranged at diametrically opposite sides of the boiler or generator 1 as clearly shown in Figs. 1, 2 and 3 of 90 the drawings. In a manner and by means which will presently be fully described, water contained in either pumping cylinder is to be discharged therefrom through the admission of live steam from the generator 95 1 into the respective cylinder, the steam being subsequently permitted to exhaust and being condensed whereby to create a partial vacuum within said pumping cylinders for the purpose of replenishing the cylinders 100 with a further volume of water. The numeral 4 indicates a valve casing which is arranged above the generator 1, and a pipe 5 leads from the live steam space of the boiler or generator 1 to the said valve casing 4 preferably through the lower side thereof as clearly shown in Figs. 4 and 5 of the drawings.

Steam conducting pipes 6 and 7 lead from the diametrically opposite sides of the valve casing 4 to the upper ends of the pumping cylinders 2 and 3 respectively, and rotatably arranged within the valve casing is a three-

way valve 8 having an inlet port 9 which is at all times in communication with the discharge end of the steam supply pipe 5. The valve 8 is further provided with outlet ports 10 and 11 which in the operation of the valve, as will be presently explained, are to be successively brought into communication with the steam conducting pipes 6 and 7 respectively. Thus when the outlet port 10 is 10 in communication with the pipe 6 as shown in Fig. 5, steam from the generator 1 will pass through the pipe 5 into the valve 8 through the port 9 and out through the port 10 and pipe 6 to the pumping cylinder 2, and 15 when the valve is oscillated so as to bring the port 11 into communication with the pipe 7, the supply of steam to the pipe 6 will be cut off and the steam will pass through the said port 11 into the pipe 7 and to the 20 pumping cylinder 3.

Steam is permitted to exhaust from the pumping cylinders 2 and 3 through valve chambers 12 and 13 respectively within which are arranged check valves 14 and 15, 25 respectively, automatically moved with relation to their seats in a manner which will be presently explained. The exhaust steam passing through the valve casings 12 and 13 enters other valve casings indicated by the 30 numerals 16 and 17 and in communication with the said valve casings 12 and 13 respectively. Each of the valve casings 16 and 17 has a downwardly extending inlet branch 18 and a substantially horizontally disposed branch 19, and working in the branches 19 of the casings 16 and 17 respectively are piston valves 20 and 21. Each casing 16 and 17 has an outlet port 22 which in one position of the respective valve 20 or 21 as 40 the case may be, is closed and in another position of the respective valve is uncovered. As will be presently explained these outlet ports 22 are in communication with respective condensers for the steam. A rod 23 45 extends between and is rigidly connected with the pistons 20 and 21, the rod fitting in a fluid-tight manner through the adjacent ends of the branches 19 of the valve casings 16 and 17 and being yet capable of reciprocating motion. In practice the piston valves 20 and 21 are so spaced by the rod 23 that when either valve is closed the other valve will be open. The rod 23 extends above and to one side of the valve casing 4, and the 55 valve 8 is provided with a stem 24 which extends exteriorly of its casing and has fixed to it an arm 25 having a pin and slot connection 26 with the rod 23.

To each of the check valves 14 and 15 60 there is connected a rod 27 extending downwardly into the respective pumping cylinder 2 or 3 as the case may be. Arranged within the cylinders 2 and 3 are floats indicated by the numerals 28 and 29 respectively, and these floats are suitably mounted

upon the respective rods 27 so that they may slide vertically thereon. For a purpose to be presently explained the external diameter of each float is nearly equal to the internal diameter of the respective pump 70 cylinder so that there is only a relatively narrow space between the exterior surface of each float and the inner surface of the wall of the respective cylinder. Near its upper end each rod 27 is provided with an 75 abutment 30 which may be permanently fixed in place or adjustably secured upon the rod either as desired. Likewise each rod is provided near its lower end with an abutment 31, and below their abutments 31, the 80 rods fit slidably through suitable guides 32 within the respective pumping cylinders so as to be guided in the vertical movement which they are designed to have as the floats rise and fall and coat with the abutments 85 30 and 31, as will be presently explained. The seats for the valves 14 and 15 are indicated respectively by the numerals 33 and 34 and these valves are, of course, designed to engage their seats when they are moved 90 in an upward direction through the lifting of the respective rods 27 by the rise of the respective floats 28 or 29 as the case may be.

The numeral 35 indicates a water supply pipe for the pumping apparatus and this 95 pipe is provided with branches 36 and 37 in which are interposed check valves 38 and 39 respectively. The branches 36 and 37 communicate respectively with the lower ends of the pumping cylinders 2 and 3, the 100 water delivered by the pipe 35 passing through the branches 36 and 37 and past the respective check valves into the said respective cylinders. Pipes 40 and 41 are connected with the branches 36 and 37 respectively and communicate with a water conducting pipe 42. Check valves 43 and 44 are interposed in the pipes 40 and 41 respectively, and are designed to open in the direction of flow of water through the 105 respective pipes 40 and 41 to the pipe 42, the said pipes 40 and 41 being placed in communication with the pumping cylinders 2 and 3, respectively, through the branches 36 and 37 at points in these branches between the said respective cylinders and the 110 check valves 38 and 39. Leading from the pipe 42 are branch pipes 45 and 46 which respectively lead to condensers indicated in general by the numerals 47 and 48. The 115 said pipes 45 and 46 discharge into pipe coils 49 and 50 located within the casings 51 and 52 of the condensers 47 and 48 respectively. The coils 49 and 50 discharge in turn into branch pipes 53 and 54 which 120 connect with a main discharge pipe 55 through which water is delivered from the apparatus. As before stated, the outlets 22 from the valve casings 16 and 17 are in communication with the condensers and this 125 130

communication is preferably established by pipes 56 and 57 leading respectively from the casings 16 and 17 to the lower ends of the casings 51 and 52. For a purpose to be presently explained, pipes 58 and 59 are arranged with their upper ends in communication with the pumping cylinders 2 and 3, respectively, near the upper ends of the latter, and at their lower ends these pipes 10 communicate with the water spaces of the boiler or generator 1 near the lower end thereof, check valves 60 and 61 being interposed in the pipes 58 and 59 respectively, and opening in the direction of flow of 15 water through the pipes to the said boiler or generator.

Assuming that the pumping cylinder 2 is filled with water substantially to the level shown in Fig. 2 of the drawings and that the 20 water in the cylinder 3 is at the lower level shown in the said figure, the valves being in the positions shown in Fig. 2 of the drawings, the operation of the pumping apparatus is as follows: The live steam generated 25 in the boiler 1 will pass through the pipe 5 into the valve 8 and through the pipe 6 and into the pumping cylinder 2 at the top thereof. The pressure of the steam against the upper end of the float 28 and the surface of 30 the water surrounding this float will result in the water contained in the pumping cylinder 2 being forced out through the branch pipe 40 and past the valve 43 to the pipe 42. The float 28, of course, lowers with the level 35 of the water within the pumping cylinder 2 and in such movement recedes from the abutment 30 upon the respective rod 27. However, the pressure of the steam acting against the under side of the check valve 14 will 40 maintain this valve in closed position. At this point it may be stated that inasmuch as the space between the exterior of the float 28 and the inner surface of the wall of the pumping cylinder 2 is relatively narrow, 45 there will be but little loss of steam by condensation through contact with the water which is at a lower temperature, the upper end of the float 28 receiving the maximum pressure as it is of a diameter nearly equal to 50 the internal diameter of the pumping cylinder. For the same reasons the water within the pumping cylinder will not become heated to any undesirable high degree of temperature through absorption of heat 55 from the steam. As stated the water is delivered from the pumping cylinder to the pipe 42 and from this pipe the water passes through the two branches 45 and 46 to the respective coils 49 and 50 in the condensing 60 chambers 51 and 52, finally passing out through the branches 53 and 54 to the delivery pipe 55. At a predetermined point in its lowering movement, the float 28 will come in contact at its lower end with the 65 abutment 31 and when the water level with-

in the pumping cylinder has fallen to such a point that the float is no longer buoyed its weight will be imposed upon the valve rod 27 moving the same downwardly and thus opening the valve 14 against 70 the pressure of the live steam within the said pumping cylinder. The steam will then exhaust through the valve casing 12 and past the valve 14 into the downward branch 18 of the valve casing 16 but this branch is closed 75 in a fluid-tight manner by the piston valve 20. The pressure of the steam against this valve 20 will then act to move the valve to the right in Fig. 2 of the drawings so as to uncover the outlet port 22 and in such movement of the valve, corresponding motion will be imparted to the valve 21 moving the same from the position shown in Fig. 2 to position closing the outlet port 22 from the valve casing 17. Likewise through the movement 80 of the valve 20 and the rod 23 connected therewith, the three-way throttle valve 8 will be rotated in a clockwise direction thus closing the supply of live steam to the pipe 6 and bringing the outlet port 11 of the said valve 90 into communication with the pipe 7 so that live steam will be admitted from the generator 1 into the pumping cylinder 3. When the valve 20 moves in the direction stated above and uncovers the port 22, the exhaust 95 steam will pass upwardly through the pipe 56 and into the condensing chamber 51 of the condenser 47 and coming in contact with the water cooled coils 49 will be condensed thus creating a partial vacuum within the pumping cylinder 2, the water of condensation flowing downwardly through the pipe 56 and valve casing 16 into the said pumping cylinder. Due to the creation of this partial 100 vacuum, water will be drawn in from the supply main 35 through the branch 36 and past the valve 38 to the pumping cylinder until it reaches approximately the level shown in Fig. 2 of the drawings. As the water level rises in the pumping cylinder 2, 105 the float 28 will be carried upwardly until, striking against the abutment 30, it moves the valve rod 27 in an upward direction to seat the valve 14 and thus provide against escape of live steam when next admitted into 110 the pumping cylinder. The upper end of the pipe 58 communicates with the cylinder 2 at a point above the level of the water within the boiler or generator 1 and as the highest 115 water level in the pumping cylinder reaches a point above the point of communication of the upper end of the pipe 58 with the cylinder, when live steam is next admitted to the cylinder, a greater or less volume of water 120 will be discharged from the cylinder downwardly into the pipe 58 and past the check valve 60 into the water space of the boiler or generator 1. Of course, the operation just described is carried out in the pumping cylinder 3 and the parts associated therewith, 125 130

water being discharged from one of the cylinders while it is being drawn into the other cylinder. While the water in either pumping cylinder does not, through absorption of 5 heat from the live steam, become heated to an undesirable high degree of temperature, nevertheless a portion of its volume is appreciably heated and this portion will, of course, constitute the upper strata and in this 10 respect it is to be noted that it is from this heated strata that water for feeding the boiler or generator 1 is carried through the pipes 58 and 59 so that the water in the pumping cylinders as it becomes heated is 15 carried off to the boiler or generator where its contained heat units are of advantage. As a general proposition, however, the pumping apparatus will deliver cold water or, in other words, will deliver water substantially at the 20 same temperature at which it enters the apparatus.

Having thus described the invention, what is claimed as new is:

1. In pumping apparatus, pumping cylinders, a conduit for the liquid to be pumped communicating with each cylinder, an outlet from each cylinder for the liquid, a source of fluid pressure supply in communication with the cylinders, a valve for controlling the passage of the pressure fluid to the cylinders, a valve-controlled exhaust from each cylinder for the pressure fluid, and means actuated by the pressure fluid passing through the exhaust for automatically setting the valve controlling the passage of fluid to the cylinders.

2. In pumping apparatus, pumping cylinders, a conduit for the liquid to be pumped communicating with each cylinder, an outlet from each cylinder for the liquid, a source of fluid pressure supply in communication with the cylinders, a valve for controlling the passage of the pressure fluid to the cylinders, a valve-controlled exhaust from each cylinder for the pressure fluid, piston valves controlling the outlet of each exhaust and open to the pressure of the fluid passing through the exhaust, and operative connections between the piston 45 valves and the first mentioned valve for automatically actuating the latter.

3. In pumping apparatus, pumping cylinders, a conduit for the liquid to be pumped communicating with each cylinder, an outlet from each cylinder for the liquid, a source of fluid pressure supply in communication with the cylinders, a valve for controlling the passage of the pressure fluid to the cylinders, a valve-controlled exhaust from each cylinder for the pressure fluid including a casing having an outlet, a piston valve working in each casing and movable into and out of position to close the respective outlet, said valve being exposed to the 60 pressure of fluid passing through the ex-

haust and operative connections between the piston valves and the first mentioned valve.

4. In pumping apparatus, pumping cylinders, a conduit for the liquid to be pumped communicating with each cylinder, an outlet from each cylinder for the liquid, a source of fluid pressure supply in communication with the cylinders, a valve for controlling the passage of the pressure fluid to the cylinders, a valve-controlled exhaust from each cylinder for the pressure fluid including a casing having an outlet, a piston valve working in each casing and movable into and out of position to close the respective outlet under the influence of the pressure fluid passing through the exhaust, means extending between and connecting the piston valves, and an operative connection between the said means and the first mentioned valve for actuating the latter when the piston valves are moved.

5. In pumping apparatus, pumping cylinders, a conduit for the liquid to be pumped communicating with each cylinder, an outlet from each cylinder for the liquid, a source of fluid pressure supply in communication with the cylinders, a valve for controlling the passage of the pressure fluid to the cylinders, an operating arm extending from the valve, a valve-controlled exhaust from each cylinder for the pressure fluid including a valve casing having an outlet, a piston valve working in each of the said casings and exposed to the pressure of the fluid flowing through the exhaust and movable to position to close the respective outlet and to position to uncover the same, and means extending between and connecting the said piston valves and operatively connected with the operating arm of the first mentioned valve.

6. In pumping apparatus, pumping cylinders, a conduit for the liquid to be pumped communicating with each cylinder, an outlet from each cylinder for the liquid, a source of fluid pressure supply in communication with the cylinders, a valve for controlling the passage of the fluid pressure to the cylinders, an exhaust from each cylinder for the pressure fluid, a float actuated valve for controlling the exhaust from each cylinder, a valve casing in communication with the exhaust beyond each float actuated valve, a piston valve working in each casing and exposed to the pressure of the fluid flowing through the exhaust, each casing having an outlet controlled through the movement of the respective piston valve, and means operatively connecting the piston valves with the first mentioned valve.

7. In pumping apparatus, pumping cylinders, a conduit for the liquid to be pumped communicating with each cylinder, an outlet from each cylinder for the liquid, a source of fluid pressure supply in com-

5
munication with the cylinders, an automatically operating valve for directing the passage of the pressure fluid into one cylinder and simultaneously cutting it off from the other cylinder, an exhaust from each cylinder for the pressure fluid, a valve for controlling each exhaust, a rod leading from each valve into the respective pumping cylinder and having spaced abutments thereon, 10 and a float in each cylinder movable along the rod and operating between the said abutments.

8. In pumping apparatus, pumping cylinders, a conduit for the liquid to be pumped communicating with each cylinder, an outlet from each cylinder for the liquid, a source of supply of a condensable fluid under pressure in communication with the cylinders, means for controlling the passage 20 of the pressure fluid to the cylinders, an exhaust from each cylinder for the pressure fluid, a condenser in communication with each exhaust, and means controlled by the flow of pressure fluid through the exhaust 25 for operating the means for controlling the passage of pressure fluid to the cylinders.

9. In pumping apparatus, pumping cylinders, a conduit for the liquid to be pumped communicating with each cylinder, an outlet from each cylinder for the liquid, a source of supply of a condensable fluid under pressure in communication with the cylinders, means for controlling the passage 30 of the pressure fluid to the cylinders, exhausts from the cylinders for the pressure fluid, condensing chambers in communication with the respective exhausts, coils within the respective condensing chambers for conducting the exhaust fluid from the 35 respective cylinders and means actuated by the

pressure fluid flowing through the exhaust to operate the means for controlling the flow of pressure fluid to the cylinders.

10. In pumping apparatus, pumping cylinders, a conduit for the liquid to be pumped 45 communicating with each cylinder, an outlet from each cylinder for the liquid, a source of supply of a condensable fluid under pressure in communication with the cylinders, a valve for controlling the passage 50 of the pressure fluid to the cylinders, an exhaust from each cylinder for the pressure fluid, float actuated valves automatically controlling the discharge of fluid through the exhausts, a valve casing in 55 communication with each exhaust and having an outlet, a piston valve working in each casing for controlling the outlet, means providing for simultaneous actuation of the said piston valves and the first mentioned 60 valve, a condensing chamber in communication with the outlet from each valve casing, and a coil in each condensing chamber in communication with the liquid outlet from the respective cylinder.

11. In pumping apparatus, a steam generator, pumping cylinder, a conduit for the liquid to be pumped communicating with each cylinder, an outlet from each cylinder for the said liquid, a valve for directing the 70 passage of the steam to one cylinder and simultaneously cutting it off from the other cylinder, a steam exhaust from each cylinder, means for automatically controlling the passage of the steam through the exhaust, 75 and means actuated by steam passing through the exhaust for operating said valve.

In testimony whereof I affix my signature.
THOMAS A. KILLMAN. [L. s.]
